UNITED STATES PATENT OFFICE.

WARREN A. SAUL, OF BRIDGEPORT, CONNECTICUT.

TIE-PLATE AND RAIL-BRACE.

1,058,337.

Specification of Letters Patent.

Patented Apr. 8, 1913.

Application filed November 6, 1912. Serial No. 729,890.

To all whom it may concern:

Be it known that I, WARREN A. SAUL, a citizen of the United States, residing at Bridgeport, in the county of Fairfield and 5 State of Connecticut, have invented a new and useful Tie-Plate and Rail-Brace, of which the following is a specification.

The present invention relates to improvements in a combined tie plate and rail brace.

10 The primary object of this invention is the provision of a tie plate disposed to be placed upon the upper surface of the tie and below the rail base and have coacting therewith a rail brace disposed at an angle 15 to engage under surface at one side of the tread of the rail and one base flange adjacent to the tie plate, a peculiar form of spike being employed to maintain the rail brace in wedged position and to at the same time, 20 spike the rail and tie plate upon the tie, the body of the rail brace being inclined and out of contact with the adjacent face of the web of the rail so that the only point of contact is with one end of the rail base and primarily 25 against the under side of the tread and the immediate adjacent portion of the web.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within 35 the scope of what is claimed without departing from the spirit of the invention.

In the drawings—Figure 1 is a perspective view of the tie plate and rail brace showing a tie, spike and rail and adjacent 40 portion of the rail in dotted lines. Fig. 2 is a cross section through the tie plate and rail brace in operable relation to the rail shown in dotted lines. Figs. 3 and 4 are detailed views of the spike employed in connection 45 with the tie plate and rail brace.

Referring to the drawings, the numeral 1 designates the tie which has placed thereupon the metal tie plate 2, provided with the apertures 3 for the reception of the spikes 50 as will presently appear. The base 4 of the rail is disposed upon the tie plate in the usual manner between the aligned apertures 3 while disposed to engage the base of the rail, the tie plate and also the rail at the junction of the web and tread is a rail brace 5, which is constructed with a bracing por-

tion disposed to be placed inclined from the outer edge of the base flange of the rail toward the junction of the web and tread of the rail, as clearly shown in Figs. 1 and 2. 60 This rail brace is provided with the compound inclined portions 6 and 7 at its lower end for engagement respectively, with the upper surface of the base 4 of the rail while the flat face 8 engages the tie plate outside 65 of the rail base, as clearly shown in Fig. 1. The upper end 9 of the rail brace is reinforced and is provided with the web engaging face 10 and the tread engaging face 11, both of which are so formed as to permit of 70 the brace 5 being wedged thereagainst to form a rigid support or brace at the underside of the tread and the portion adjacent to the upper end of the web of the rail. By constructing the head 9 as clearly shown, the 75 contacting portions thereof may be readily slid upwardly upon the web of the rail so that the portion at 11 will properly engage the underside of the tread of the rail.

Formed in the compound curved portions 80 6 and 7 of the brace intermediate of the ends of the brace, is a slot 12, having the two parallel walls 13 and the dove-tailed shaped portion 14, said slot being so disposed as to have its open end above one of the apertures 85 3 of the tie plate, while the dove-tailed portion is above the edge of the base 4 of the rail.

By inclining the plate 5 as indicated in Figs. 1 and 2, the maximum bracing power 90 is exerted directly upon the under surface of the tread, the adjacent portion of the web acting as a guiding portion for the enlarged head 9 of the rail brace plate 5, while the portion engaging the tie plate and the base 95 4 of the rail retains the plate in such inclined position so that the strain from the tread will be directly upon the inclined portion of the rail brace plate 5.

A spike 15, as clearly shown, is preferably 100 employed in connecting the tie plate, rail and the rail brace 5 in the positions as shown in Figs. 1 and 2, and is provided with the dove-tailed wedging head 16, for coaction with the dove-tailed head 14 of the slot of 105 the rail brace, and with the parallel walls 17 which fit between the parallel walls 13 of the slot 12. Oppositely disposed lugs 18 provide a means for engaging the tie plate 2 upon opposite side of the aperture 3 beyond the outer edge of the rail brace 5, so that when the spike is driven home into

the tie 1, the shank portion passing through the aperture 3 of the tie plate, the lugs 18 will engage the tie plate 2 beyond the outer edge of the lower flange 7 of the rail brace 5, coacting with the inclined face of the flange 7 to move the rail brace 5 inwardly and toward the rail, so that the curved portions 6 and 7 will engage the rail base 4, as clearly shown in Figs. 1 and 2, while the 10 head 9 will be forced upwardly into rigid contact with the web and under surface of the tread of the rail, the dove-tailed shaped head 16 of the spike entering the dove-tailed recess 14 and thus assisting in locking 15 the rail brace 5 against outward displacement and at the same time having the under surface of the dove-tailed head 16 engage the base 4 of the rail and hold the rail downwardly upon the tie plate and tie. The 20 dove-tailed head 16 also has the coacting wedging effect to assist in forcing a rail brace 5 into proper engagement with the rail.

What is claimed is:

25 1. The combination with a tie plate, a rail and a rail brace, said rail brace having a lower inclined rail base engaging edge provided with a substantially dove-tailed recess

intermediate of its ends, of a spike for piercing the tie plate having a head for insertion within the recess of the rail brace to engage the rail base and with lugs for engaging the tie plate and the adjacent portion of the lower edge of the rail brace, the head and recess combining to hold the brace 35 against longitudinal movement while the lugs hold the brace against outward displacement.

2. The combination with a rail, a tie plate and a rail brace, of a spike for piercing the 40 tie plate and a tie, having a head with oppositely disposed lugs for engaging the tie plate and the adjacent portion of the rail brace to retain the rail brace against outward displacement and to wedge the same 45 into engagement with a rail, said head further being provided with an enlarged portion for engagement with the rail base.

In testimony that I claim the foregoing as my own, I have hereto affixed my signature in the presence of two witnesses.
